FIG. 1.

FIG. 2.

FIG. 3.

FIG. 4.

FIG. 1 is a side elevation of a diving board platform embodying our new design, with a diving board and support shown in dotted lines for illustrative purposes only;

FIG. 2 is a top plan view of the diving board platform of FIG. 1;

FIG. 3 is a rear perspective view of the diving board platform of FIG. 1; and

FIG. 4 is a front elevation of the diving board platform of FIG. 1.

The characteristic feature of our design is the flat arch of the platform, in combination with the tubular support adjacent to the front end of the platform, substantially as shown.

We claim:

The ornamental design for a diving board platform, as shown and described.
